TABLE

Thomas Winrow, Naperville, Ill., assignor to Futorian Corporation, Amsterdam, N.Y.

Filed Nov. 30, 1970, Ser. No. 26,212

Term of patent 14 years

Int. Cl. D6—03

U.S. Cl. D6—179

The figure is a perspective view of a table illustrating my new design. The side not shown is substantially identical to the side shown while the back is similar to the front, the drawer shown on the front of the table is absent from the back.

I claim:

The ornamental design for a table, substantially as shown and described.
